UNITED STATES PATENT OFFICE.

JOHN N. SISLEY, OF CONNELLSVILLE, PENNSYLVANIA, ASSIGNOR TO THE KNOCKDOWN BOX COMPANY, OF CONNELLSVILLE, PENNSYLVANIA.

KNOCKDOWN BOX.

No. 801,113.

Specification of Letters Patent.

Patented Oct. 3, 1905.

Application filed October 11, 1904. Serial No. 228,048.

To all whom it may concern:

Be it known that I, JOHN N. SISLEY, a citizen of the United States, residing at Connellsville, in the county of Fayette and State of Pennsylvania, have invented a new and useful Knockdown Box, of which the following is a specification.

The invention relates to improvements in knockdown boxes.

10 The object of the present invention is to improve the construction of knockdown boxes and to provide a simple, inexpensive, and efficient one of great strength and durability capable of affording a firm structure when set 15 up and adapted to be compactly folded when not in use.

With these and other objects in view the invention consists in the construction and novel combination and arrangement of parts hereinafter fully described, illustrated in the accompanying drawings, and pointed out in the claims hereto appended, it being understood that various changes in the form, proportion, size, and minor details of construction within 25 the scope of the claims may be resorted to without departing from the spirit or sacrificing any of the advantages of the invention.

In the drawings, Figure 1 is a perspective view of a knockdown box constructed in accordance with this invention. Fig. 2 is a longitudinal sectional view of the same. Fig. 3 is a transverse sectional view. Fig. 4 is an enlarged detail perspective view illustrating the arrangement of the angle-strips at one of the corners of the box. Fig. 5 is a horizontal sectional view of one corner of the box. Fig. 6 is a detail perspective view of a portion of the cover or top, illustrating the construction of the locking devices for securing the sections of the cover in alinement when the box is closed.

Like numerals of reference designate corresponding parts in all the figures of the drawings.

45 11 designate the sides of the knockdown box, provided at their end edges with angle-strips 2, which overlap and engage the ends 3 of the box. The ends 3 are provided at their upper and lower edges with angle-strips 50 4 and 5, which overlap and engage the top or cover 6 and the bottom 7 of the box. The top and bottom are provided at their side edges with angle-strips 8 and 9, which overlap and engage the sides 1 of the box, as

clearly illustrated in Fig. 3 of the drawings. 55 The angle-strip 2, which may be constructed of any suitable metal, is composed of flanges 10 and 11, arranged at right angles to each other, the flange 10 being secured to the side by the means hereinafter described and the 60 flange 11 extending inward from the sides and overlapping the side edge of the adjacent end 3 of the box. The flange 10 is provided at intervals with integral tongues 12, formed by 65 partially severing the metal of the flange 10 and bent inwardly at right angles to the inner face of the said flange 10. The tongues pierce the side 1 and are clenched at the inner face thereof, as shown at 13 in Fig. 2 of the drawings. The other flange 11 is imperforate, and 70 the angle-strip 2 is strengthened by corrugations 14, consisting of oppositely-tapered protuberances formed by stamping or otherwise pressing the metal outward from the inner faces of the flanges. These protuberances are 75 preferably semicircular in cross-section and taper from the angle of the strips toward the side edges thereof. Any number of the protuberances, which extend transversely of the strip, may be employed, as will be readily 80 understood. The tongues, which are preferably arranged in pairs, are spaced apart, and the protuberances are located at the spaces between the pairs of tongues. The ends 15 of the flanges are cut at an angle to provide a 85 neat fit at the corners of the box, the other flanges being correspondingly cut at the corners. As all of the angle-strips employed in the construction of the box are alike, a detail description of the strip 2 is sufficient to fully 90 explain their construction.

The bottom 7 of the box is placed upon the inwardly-extending bottom flanges of the ends 3 of the box and is interposed between the said ends 3, thereby spacing the latter and preventing the same from moving inwardly. The imperforate side flanges of the angle-strip of the bottom 7 extend upwardly, and the sides 1 are fitted against the inner faces of the side flanges and against the side edges of the ends 100 3, which space the sides of the box, and prevent the same from moving inwardly toward each other. The side flanges of the bottom 7 prevent any outward movement of the side 1 of the box. The projecting flanges of the 105 sides of the box extend inwardly on the outer faces of the ends 3 and prevent any outward movement of the same. The cover, which is

interposed between the upper portions of the ends of the box, prevents any inward movement of the same, and its end edges are engaged by the upper projecting flanges of the 5 ends of the box. The projecting portions of the angle-strips at the sides of the top of the box extend downward and engage the outer faces of the sides 1 and prevent any outward movement thereof. By this construction the 10 parts or members of the box are firmly bound together and a structure of great strength is provided.

The bottom, sides, and ends are assembled before the top or cover is placed in position, 15 and in order to enable the same to be effected the top or cover is composed of two sections, being divided transversely, as clearly shown at 16 in Figs. 1 and 2 of the drawings, and the angle-strips of the top are provided at the 20 depending flanges with overlapped perforated portions or ears, which are connected by pivots or pintles 17, whereby the two sections of the top are hinged together. One of the sections of each angle-strip is provided with a 25 projecting finger 18 and tapering outwardly, as clearly shown in Figs. 1 and 6 of the drawings, and presenting an inclined upper edge when the sections of the cover are in alinement. The projecting finger 18 is adapted 30 to engage a shoulder or stop 19 of the other section of the angle-strip, and it is retained in such engagement by its resiliency, the metal being sufficiently resilient to form a 35 spring-catch. The stop or shoulder consists of a protuberance formed by pressing the metal outwardly from its inner face, and the catch or finger is adapted to be readily sprung into and out of engagement with the same. The lower face of the protuberance which forms the 40 stop or shoulder is straight, and the upper portion of the protuberance presents a substantially inclined face for enabling the catch or finger to be readily engaged with the shoulder. In placing the top or cover on the box the sections 45 are arranged at an angle to each other, as indicated in dotted lines in Fig. 2 of the drawings, and a slight downward pressure on the sections will carry them into a horizontal position, and the catches will automatically 50 engage the stops and lock the cover or top in its closed position.

It will be seen that the knockdown box is exceedingly simple and inexpensive in construction, that the angle-strips not only connect the parts, but reinforce the same, and that the tongues which bind the angle-strips to the parts of the box obviate the necessity of employing nails or similar fastening devices.

60 Although the box shown in the accompanying drawings is oblong or of a greater length than width and although the vertical walls of the box are described as sides and ends, yet it will be readily understood that the box may 65 be made of any desired dimensions and that

the side and end walls may be of equal area. The top, bottom, sides, and ends of the box will in practice be constructed of a plurality of boards, as will be readily understood.

Having thus fully described my invention, 70 what I claim as new, and desire to secure by Letters Patent, is—

1. A knockdown box of the class described, comprising a bottom provided with upwardly-projecting side flanges, ends fitted against the 75 end edges of the bottom and having inwardly-extending top and bottom flanges, sides interposed between the side flanges of the bottom and the side edges of the ends of the box and provided at their end edges with inwardly-extending flanges overlapping and arranged on the outer faces of the ends of the box, and a top or cover interposed between the ends of the box and provided with side flanges overlapping and detachably engaging the outer 80 faces of the sides of the box, said top or cover being composed of hinged sections adapted to be arranged at an angle to enable them to be engaged with the top flanges of the ends.

2. A knockdown box of the class described, 85 comprising a bottom provided with upwardly-projecting side flanges, ends fitted against the end edges of the bottom and having inwardly-extending top and bottom flanges, sides interposed between the side flanges of the bottom 90 and the side edges of the ends of the box and provided at their end edges with inwardly-extending flanges overlapping and arranged on the outer faces of the ends of the box, and a top or cover composed of pivoted sections and interposed between the ends of the box and provided with side flanges overlapping and 95 detachably engaging the outer faces of the sides of the box, said flanges being formed by angle-strips secured to the parts of the box and 100 projecting beyond the same.

3. A knockdown box of the class described, 105 comprising a bottom, top, sides and ends provided with angle-strips forming projecting flanges for overlapping and detachably engaging the adjacent parts, said top and its angle-strips being composed of sections, and the angle-strips being pivoted together, and a 110 catch for holding the sections in alinement.

4. A knockdown box of the class described, 115 comprising a bottom, top, sides and ends provided with angle-strips forming projecting flanges for overlapping and detachably engaging the adjacent parts, said top and its angle-strips being composed of sections, and the angle-strips being pivoted together, a 120 catch consisting of a resilient finger extending from one section of the angle-strip, and a stop projecting from the other section and arranged to be engaged by the finger.

5. In a device of the class described, the combination with the body of the box having projecting end flanges, of a sectional top engaging the end flanges and provided with angle-strips composed of sections pivoted to 125

gether, a catch consisting of a resilient finger extending from one section of the angle-strip, and a stop projecting from the other section of such strip and arranged to be engaged by the finger.

- 5 6. A knockdown box, comprising a bottom provided with side flanges, ends provided at their upper and lower edges with flanges, the lower flanges being extended beneath the bottom, sides arranged between the side flanges of the bottom and provided at their ends with flanges engaging the ends of the box at the flangeless side edges thereof, said sides terminating short of the upper flanges of the ends, and a top composed of pivotally-connected sections and provided with side flanges for engaging the sides of the box, said top having its flangeless ends engaged with the top flanges of the ends of the box.
- 10 7. A knockdown box, comprising a bottom provided with side flanges, ends provided at their upper and lower edges with flanges, the lower flanges being extended beneath the bottom, sides arranged between the side flanges of the bottom and provided at their ends with flanges engaging the ends of the box at the flangeless side edges thereof, and a top composed of pivotally-connected sections provided with side flanges for engaging the sides of the box, said top having its flangeless ends engaged with the top flanges of the ends of the box.
- 15 8. A knockdown box, comprising a bottom provided with side flanges, ends provided at their upper and lower edges with flanges, the lower flanges being extended beneath the bottom, sides arranged between the side flanges of the bottom and provided at their ends with flanges engaging the ends of the box at the flangeless side edges thereof, and a top composed of pivotally-connected sections provided with side flanges for engaging the sides of the box, said top having its flangeless ends engaged with the top flanges of the ends of the box.
- 20 9. A knockdown box, comprising a bottom provided with side flanges, ends provided at their upper and lower edges with flanges, the lower flanges being extended beneath the bottom, sides arranged between the side flanges of the bottom and provided at their ends with flanges engaging the ends of the box at the flangeless side edges thereof, and a top composed of pivotally-connected sections provided with side flanges for engaging the sides of the box, said top having its flangeless ends engaged with the top flanges of the ends of the box, and a catch consisting of a resilient finger extending from one of the sections of the top, and a stop projecting from the other section and arranged to be engaged by the finger when the sections are brought into alinement.
- 25 10. In testimony that I claim the foregoing as my own I have hereto affixed my signature in the presence of two witnesses.

JOHN N. SISLEY.

H. C. SHUN.

tom, sides arranged between the side flanges of the bottom and provided at their ends with flanges engaging the ends of the box at the flangeless side edges thereof, a top composed of pivotally-connected sections and provided with side flanges for engaging the sides of the box and having its flangeless ends engaged with the top flanges of the ends of the box, and means for automatically locking the sections of the top in alinement when the same are brought into such relation.

10 11. A knockdown box, comprising a bottom provided with side flanges, ends provided at their upper and lower edges with flanges, the lower flanges being extended beneath the bottom, sides arranged between the side flanges of the bottom and provided at their ends with flanges engaging the ends of the box at the flangeless side edges thereof, a top composed of pivotally-connected sections provided with side flanges for engaging the sides of the box, said top having its flangeless ends engaged with the top flanges of the ends of the box, and a catch consisting of a resilient finger extending from one of the sections of the top, and a stop projecting from the other section and arranged to be engaged by the finger when the sections are brought into alinement.

15 12. In testimony that I claim the foregoing as my own I have hereto affixed my signature in the presence of two witnesses.
